UNITED STATES PATENT OFFICE

2,048,297

SPARK PLUG

Basil H. Savage, San Diego, Calif., assignor to
 Savage Research Corporation, San Diego,
 Calif.

Application July 5, 1933, Serial No. 679,068

4 Claims. (Cl. 123—169)

My invention relates to spark plugs, and the objects of my invention are:

First, to provide a spark plug which incorporates an auxiliary chamber communicating with the combustion chamber of the cylinder in such a manner that cooled gases are caused to spray on the insulating member and electrodes so that these parts are maintained in a clean condition, thus providing a spark plug which 10 does not readily foul;

Second, to provide a spark plug of this class in which the chamber incorporated in the spark plug is exposed to the atmosphere and provided with cooling fins so that gases from the cylinder 15 upon being compressed therein are cooled prior to return flow into the combustion chamber;

Fourth, to provide a spark plug of this class which tends to reduce vibration and check gas or detonation knock;

Fifth, to provide a spark plug of this class 20 which in no manner interferes or injures the formation of perfect mixtures of combustion in the cylinders;

Sixth, to provide a spark plug of this class in 25 which the auxiliary chamber and its communication with the combustion chamber is so arranged that combustion of gases cannot take place in the auxiliary chamber; and

Seventh, to provide on the whole a novelly 30 constructed spark plug which is durable, efficient in its actions, and which will not readily deteriorate or get out of order.

With these and other objects in view as will appear hereinafter, my invention consists of certain novel features of construction, combination, 35 and arrangement of parts and portions as will be hereinafter described in detail and particularly set forth in the appended claims, reference being had to the accompanying drawings and to 40 the characters of reference thereon which form a part of this application in which:

Figure 1 is a side elevational view of my spark plug; Fig. 2 is an enlarged partial-sectional partial-elevational view thereof taken through 2—2 45 of Fig. 1; and Fig. 3 is an enlarged transverse sectional view thereof through 3—3 of Fig. 2.

Similar characters of reference refer to similar parts and portions throughout the several views of the drawing.

Body member 1, core 2, gasket 3, clamp nut 4, electrodes 5 and 6, and shell 7 constitute the principal parts and portions of my novel spark plug.

A body member 1 is provided which is annular 55 in form and arranged with a bore 1a there-

through. One end of the body member is externally threaded, as indicated by 1b, so as to screw into the conventional spark plug opening of an internal combustion engine. The outer extremity is internally threaded as indicated by 5 1c, and is provided inwardly of the internally threaded portion with a shoulder 1d. The body member receives a core 2 which is formed of insulated material, and is provided with an enlarged portion 2a intermediate its ends adapted 10 to engage the shoulder 1d or a gasket 3 resting on the shoulder. The core is engaged from its outer portion by means of a clamp nut 4 which fits thereover and co-acts with the screw threads 1c, thereby rigidly securing the core in sealed 15 relation within the body member 1. From its secured portion the core 2 tapers towards the inner end of the body member so as to be spaced from the walls of the bore 1a. The core 2 receives an electrode 5 which extends axially there- 20 through and is provided with a terminal 5a at the outer extremity of the core 2. The inner extremity of the electrode 5 protrudes slightly beyond the inner end of the body member 1 and co-acts with the second electrode 6 secured to 25 the walls of the body member 1 and extending into contiguous but spaced relation therewith.

The external portion of the body member at its outer end is polygonal in form, as indicated by 1e, forming a tool receiving portion facilitating the tightening of the clamp nut 4. Immediately inwardly from the tool receiving portion 1e the body member 1 is provided with an annular flange 1f. A similar flange 1g is provided near the outer extremity of the screw threads 1b. 30 The two flange portions 1f and 1g are approximately equal in diameter, and the body member 1 forms therebetween a cylindrical portion 1h. The cylindrical portion 1h is intersected by a plurality of ports 1j which are directed inwardly and downwardly until they intersect the bore 1a, as shown best in Fig. 2. The several ports 1j are directed so that their axes intersect the inner extremity of the core 2.

The flanges 1f and 1g are adapted to receive 45 an annular shell member 7. The shell member is constant in section and is welded or otherwise connected in sealed relation with the flanges 1f and 1g. The shell thus forms with the cylindrical portion 1h an annular chamber, designated 50 A, which is in communication with the firing chamber of the cylinder in association with the spark plug through the ports 1j. The shell 7 is provided with a plurality of radiating cooling fins 1a. 55

Operation of these spark plugs is as follows: When the pressure in the cylinder is increasing, gases flow through the ports 1/2 into the chamber A and are cooled. When the pressure within the cylinder is diminishing, the flow is reversed so that streams of the cooled gases are directed against the inner end of the core and along the electrode 5 thereby maintaining these parts in a relatively cooled condition and preventing the accumulation of carbon deposits. Furthermore, apparently due to the slight cushioning effect obtained by the chamber A, and possibly by the air currents set up by reason of the flow of gases back and forth across the electrodes, there is a tendency to reduce or eliminate detonation knocks, particularly those knocks caused by lower grade fuels, thus it has been found that a cheaper grade of fuel may be used to an advantage in conjunction with the above illustrated spark plug. Though I have shown and described a particular construction, combination, and arrangement of parts and portions, I do not wish to be limited to this particular construction, combination, and arrangement, but desire to include in the scope of my invention, the construction, combination, and arrangement substantially as set forth in the appended claims.

Having thus described my invention, what I claim as new and desire to secure by Letters Patent is:

1. In a spark plug, a body member having an annular recess in its outer side surface, sealing means secured over and surrounding said recess supported on the outer surface of said body member for sealing said recess to the exterior,

said body member also having ports communicating between the recess and the interior of the spark plug, said ports constituting the only means of ingress or egress to or from said recess.

2. In a spark plug, a body member having a long narrow channel in its outer side surface, and an annular imperforate sealing member secured over and surrounding said channel for sealing said channel to the exterior of said body member, ports communicating between said channel and the interior of the spark plug, said ports constituting the only means of ingress or egress to or from said channel.

3. In a spark plug, a body member having a long narrow channel in its outer side surface, an annular imperforate sealing member secured over and surrounding said channel for sealing said channel to the exterior of said body member, ports communicating between said channel and the interior of the spark plug, said ports constituting the only means of ingress or egress to or from said channel, and cooling fins protruding outwardly from said annular sealing member.

4. In a spark plug, a body member having an enclosed recess therein near its outer side in its outer surface, the outer wall of said recess being imperforate and sealing said recess to the exterior of said body member, said body member also having diagonally disposed ports communicating between the recess and the interior of the spark plug, said ports constituting the only means of ingress or egress to or from said recess.

BASIL H. SAVAGE. 35
